To all whom it may concern:

Be it known that we, Louis V. Aronson II, a citizen of the United States of America and a resident of South Orange, in the county of Essex and State of New Jersey, and Warren I. Nissen, a citizen of the United States and a resident of Basking Ridge, in the county of Somerset and State of New Jersey, have jointly invented a new, original, and ornamental Design for a Cigar Lighter or Similar Article, of which the following is a specification, reference being had to the accompanying drawing, forming part thereof, in which:

Fig. 1 is a perspective view of a cigar lighter, showing our new design.

Fig. 2 is a front elevational view thereof, the top being shown in closed position; and

Fig. 3 is a top plan view.

We claim:

The ornamental design for a cigar lighter or similar article, substantially as shown.
